TYPEWRITER RIBBON AND THE LIKE

Herbert L. Shaller, Philadelphia, Pa.

Application August 26, 1931. Serial No. 559,543

7 Claims. (Cl. 197—172)

This invention relates to typewriter and the like ribbons, and more particularly to ribbons having plural longitudinal strips of different inking thereon.

Present day printing ribbons for typewriters and like machines usually become unserviceable by perforation of the tape or by the drying or exhaustion of the ink deposit thereon. The normal links employed for such ribbons comprise 10 coloring matter and a substantially non-drying vehicle. If the deposit is too heavy the ribbon is smutty in use and tends to besmear the paper adjacent the point of impact of the type, and hence it is not feasible to extend the life of a ribbon by making it moister than a certain predetermined limit for the particular tape and the particular ink material.

Present day typewriters are of the "visible" printing type and have a ribbon holding device 20 for maintaining the upper edge of the ribbon below the typed line when the machine is at rest, and for raising the ribbon prior to the impact of type. The machines normally have a "ribbon shift" which permits the ribbon holding device 25 to be lifted slightly at type impact, whereby to present a portion of the ribbon adjacent its upper edge, or for raising the ribbon holder to a greater extent so that typing occurs near the lower edge of the ribbon. These are respectively 30 known as the "black" position of the color shift key and the "red" position thereof, as in the first corresponding position of the shift key the upper or black portion of a two-color ribbon is employed, while in the "red" position of the color 35 shift key the lower or red portion of the ribbon is employed. Since the ribbon holder must move upwardly for a greater distance when the color shift key is in the "red" position, the time required for this movement and the return therefrom is 40 greater, and more energy is needed than in the "black" position. Hence, in employing a singly colored ribbon in such a typewriter, the work is normally less speedy when the color shift key is in the "red" position than when it is in the "black" position. Therefore, it is advantageous 45 to reverse the normal single-color ribbon after substantial exhaustion of its upper portion by removing it from the ribbon holder and rotating its plane through 180°. Such a procedure, however, 50 means a curling of the ribbon between the ribbon holder and the ribbon spools by a half turn at each side of the ribbon holder. As the ribbon is fed from a spool, by traction from the other spool, ultimately a pull is exerted by reason of 55 the operation of the ribbon feed reversing de-

vices of the typewriter so that the formerly driven spool is disconnected, and its supply of ribbon is now drawn back through the ribbon holder by positive rotation of the spool which has just been emptied of ribbon. The tractions or pulls on the ribbon often lead to the dragging of the curl forward onto the spool or through the ribbon holder so that in effect the ribbon is creased and no longer is it fed in the desired manner, since the edges have again been reversed into the former position and now the exhausted edge is again presented for the type impact.

In my co-pending application, Serial No. 385,- 883, filed August 14, 1929, I have set forth a ribbon inking machine by which a predetermined 70 layer of ink material is prepared on a roller and then delivered to the tape. No squeezing is employed to wipe off any excess deposit from the tape, and hence the fibers of the tape are not crushed and yet a predetermined deposit of great 75 uniformity is attained. It is now proposed to employ a machine of this type for depositing two lengthwise strips of material upon a tape, one of these strips providing a light ink deposit for the upper edge of the ribbon in its normal em- 80 ployment, while the other deposit is heavier and preferably includes an oil retaining substance such as carbon black for preparing a thick coating upon the lower portion of the ribbon. These 85 coatings may be of any desired relative quantity. It is preferred, however, to have the upper inking below the saturation point of the tape, while the lower inking is normally at this saturation point.

In employing the ribbon, the normal typing on 90 the lightly inked strip causes a tentative exhaustion of this portion of the ribbon, and this exhaustion causes a capillary delivery of liquid from the more heavily coated lower edge of the ribbon. It will be understood that a normally light inking 95 is such as to substantially fill the pores of the tape, and thus prevent the capillary travel of the ink material from the lower portion.

Owing to this constant replacement of the ink material, the upper portion of the ribbon may 100 be employed for much longer periods of time than with the standard singly inked ribbon. Furthermore, when the lower edge is coated with a colored material or ink, the typist may lay emphasis on certain words or letters by operating 105 the color shift key so that such letters are written by type impact against the more heavily inked or lower portion of the ribbon. In such a case, the two strips are inked with pigments of the same color, but with different quantities of ink, 110

and preferably with the employment of an oil retaining pigment such as carbon black for the heavier deposit.

As a modification, it is also possible to include 5 in the ink material for the lower strip a moisture absorbent material such as glycerine for absorbing moisture from the air to maintain the softness of the lower coating, and hence, by capillary transfer, the upper strip coating as needed.

10 An illustrative form of the ribbon is set forth in the accompanying drawing, in which:—

Figure 1 shows a spool having a portion of ribbon extending therefrom.

15 Figure 2 shows on a larger scale a fragment of the ribbon.

Figure 3 is a specimen of the typewriting, showing the emphasis imparted by moving the color shift key, when the ribbon has two strips of colored ink material.

20 In the drawing the spool 10 may be of any type normal for the machine upon which it is to be employed. The ribbon comprises the usual tape having a lightly inked upper portion 11 and a more heavily inked lower portion 12 providing 25 adjacent lengthwise strips on the tape.

During the course of employment of the ribbon, as the more lightly inked portion 11 delivers its ink to the paper, this tentative exhaustion is made good by the upward capillary travel of ink 30 material from the lower more heavily inked portion 12, as represented by the arrows in Figure 2.

In Figure 3, the upper two lines illustrate the work done by typing with impact against the ink strip 11, while the lower line illustrates the 35 effect by shifting for type impact against the lower portion 12 of the ribbon.

The two strips are of the same color, so that the upward capillary travel of material from the strip 12 into the strip 11 does not change the 40 character of the work done by the machine, and hence the ribbon may be employed for a much longer period while delivering a standard shade of typewriting work.

45 In an illustrative example of the coatings employed for the adjacent parallel strips, the composition of coloring for the upper or normal typing strip or side of the ribbon may comprise a mixture of one-half base color or aniline dye, as for example, material commercially known as 50 "Nigrosine Base", and one-half carbon black. The coloring material for the heavy or lower side of the ribbon may comprise approximately 25% of the base color or aniline dye, about 60% of carbon black, and 15% of a toning blue pigment such as the Prussian blue commercially known as "X-712". Both the carbon black and the toning blue were of low specific gravity and had a high oil absorption value. Similar vehicles were used in both compositions, comprising non-drying oils of animal, vegetable, or mineral origin. The two coatings may contain vehicle and coloring matter in the same proportions, such as 2½ lbs. of a non-drying vegetable oil to 1 lb. 60 of coloring matter. The tape employed was the ordinary typewriter cloth of long fiber Egyptian cotton with a thread count of 304 threads to the square inch. A dozen ribbons received a coating comprising about one ounce of ink on the light portion and about two ounces of ink on the heavy portion or a total quantity of three ounces of ink per dozen ribbons. In comparison, with ordinary ribbons having uniform inkings for the entire width, about two ounces would be employed.

Further, the compositions for the upper and lower strips may be quite different. The above mentioned position may be employed for the lower or reservoir strip in the proportion of two pounds of oil to one pound of coloring matter: while the upper or normal typing strip may have its coating comprised of as much as six or eight pounds of oil to one pound of a mixture of 45% of the base color, 45% of carbon black, and 10% of the toning pigment. As before, it is preferred to have a much heavier deposit upon the reservoir strip than upon the normal typing strip, as this affords opportunity for a better action of the lower strip as a reservoir upon exhaustion of the upper strip, and a continuance of the 80 typing with substantially the same degree of blackness for a long period of time.

The quantity of ink employed at the upper or light side may be varied according to the degree of ink (and hence lightness or darkness of the impression desired). The inking of the heavy or lower side remains substantially constant, so that maximum reservoir capacity is obtained. In some instances it is desirable to employ the vehicle without coloring material in the usual 90 sense, but with a substantially colorless absorbent which likewise holds the vehicle and 100 renders it as needed by the typing strip.

It is obvious that the invention is not limited to the employment of any particular pigments 105 or ink materials, so long as the deposit upon one strip 11 is lighter than the deposit upon the other strip 12, and the relationship of the coatings is such that the strip 11 in normal storage resists the penetration by capillary transfer of 110 ink material from the strip 12, but upon tentative exhaustion by employment or by the drying of the vehicle in the strip 11, this transfer takes place.

Having thus described the invention, what I 115 claim as new and desire to secure by Letters Patent, is:—

1. A printing ribbon having a relatively light ink deposit along one lengthwise strip thereof and a relatively heavy ink deposit of a 120 pigment of the same color and having a high oil-absorption value along a strip adjacent thereto, said heavy ink deposit serving as a reservoir to maintain the moistness of the light ink deposit as said light deposit becomes exhausted by 125 drying or use.

2. A printing ribbon having two adjacent lengthwise strips of ink deposit thereon, one strip comprising a relatively light deposit and the other a relatively heavy deposit of ink 130 materials of the same color.

3. A spool of typewriter ribbon comprising a spool and a ribbon thereon, said ribbon having two adjacent lengthwise strips of ink deposit thereon providing two individual portions for 135 type impact, the upper strip comprising a light deposit and the lower a heavy deposit of ink materials of the same color.

4. A printing ribbon having two adjacent lengthwise strips of ink deposit thereon, one 140 strip comprising a relatively light deposit of ink materials substantially free of moisture absorbent material, and the other strip comprising a relatively heavy deposit of ink materials containing a moisture absorbent material.

5. A printing ribbon having adjacent parallel strips with deposits thereon of different vehicle content, the normal typing strip including coloring matter, and the other strip being a reservoir strip including an absorbent for the vehicle 150

and containing more vehicle than the typing strip.

6. A printing ribbon having adjacent parallel strips of ink deposit thereon, one strip being the 5 normal typing strip and comprising ink materials substantially free of moisture absorbent material, and the other strip being a reservoir strip containing ink vehicle and a moisture absorbent material.

10 7. A printing ribbon having adjacent parallel

strips of ink deposit thereon, one strip being the normal typing strip and comprising ink vehicle and coloring matter, the other strip being a reservoir strip containing a greater quantity of ink vehicle and a vehicle-absorbing coloring matter for normally holding such greater quantity of vehicle and permitting the same to feed by capillary attraction into said typing strip as the vehicle becomes exhausted thereon.
